[57] ABSTRACT

A puffer-type compressed-gas circuit interrupter is provided having a movable cylinder movable with the movable contact structure, and being provided with a hollow contact follower disposed within the moving contact structure. The hollow contact follower has a lost-motion connection with the movable contact structure, and maintains abutment and a blocking of the gas flow with the hollow stationary contact until a predetermined time, thereby blocking the venting action, and permitting a pre-compression of the gas.

Further opening motion of the movable cylinder and the movable contact structure pulls the hollow contact follower away from the hollow stationary contact, and provides a double-flow venting action through both the stationary hollow contact and also the moving hollow contact.

FIG. 4

PUFFER-TYPE COMPRESSED-GAS CIRCUIT INTERRUPTER WITH DOUBLE-FLOW ACTION

CROSS-REFERENCES TO RELATED APPLICATIONS

In United States patent application filed Jan. 8, 1968, Ser. No. 696,415, now abandoned, and continued in United States patent application, filed No. 3, 1972, Ser. No. 303,579 by Stanislaw A. Milianowicz, entitled "Gas-Blast Circuit Interrupter With Insulating Arc Shield", there is illustrated and described a puffer-type circuit interrupter in which a stationary nozzle blocks flow of the piston-generated gas pressure into the arc column, until a predetermined time during the opening operation, at which time the gas flows in opposite directions through both a stationary hollow contact, and also a moving hollow contact.

BACKGROUND OF THE INVENTION

It has been known for many years by those skilled in the art that arc interruption may take place by means of piston structures operated mechanically and, in some instances, being assisted by arc generated pressure, or by differential-piston action. An example of such a type of puffer interrupter is set forth in United States patent, issued Oct. 18, 1960, to Winthrop M. Leeds, as U.S. Pat. No. 2,957,063, and assigned to the assignee of the instant application. There are many other United States patents illustrating various types of piston structures utilized to compress gas, and to force the compressed gas into the arc to effect its extinction. Some of these patents are as follows: U.S. Pat. Nos. 2,788,418 — Owens et al.; 3,331,935 Milianowicz; 2,979,591 — Friedrich and 3,524,957 — Frink.

According to the present invention, it is desired to provide an improved puffer-type circuit interrupter in which a spring-biased arcing contact follower blocks the vent in the hollow stationary contact until the pumping cylinder, finger-contact assembly, and insulating flow guide have moved a predetermined distance. This permits thereby a pre-compression of the gas, such as sulfur-hexafluoride (SF_6) gas, for example, until the follower separates from the stationary contact and draws an arc. At this time, the compressed gas is directed into the arc column, and thence through both the hollow vented follower and also the hollow tubular stationary contact, thereby giving a double-flow gas-blast action of the arc for maximum arc-interrupting effectiveness.

Accordingly, it is a general object of the present invention to provide an improved puffer-type circuit interrupter in which pre-compression of the gas occurs, until a proper subsequent time at which the arc is drawn, and the pre-compressed gas utilized to effect rapid arc extinction.

Another object of the present invention is the provision of an improved puffer-type circuit interrupter in which pre-compression of the gas occurs during a finite time, by the utilization of a hollow contact follower, having a lost-motion connection with respect to the moving-contact structure, and the device being such that in the open-circuit position, there are no creepage paths along insulating surfaces in the fully-open circuit position of the device.

Still a further object of the present invention is the provision of an improved piston-type circuit interrupter utilizing a movable hollow cylinder sliding over a sta-

tionary fixed piston, the moving hollow cylinder having attached therewith an orifice structure, hollow movable contact structure, having interiorly disposed therewithin a hollow contact follower.

Still a further object of the present invention is the provision of an improved puffer-type circuit interrupter of the type set forth in the immediately preceding paragraph, having in conjunction therewith, an interiorly-disposed arc-catcher to provide a termination point for the end of the arc column at a favorable location within the hollow contact follower.

Another object of the present invention is the provision of an improved puffer-type circuit interrupter having the capacity for pre-compression of the gas, and involving relatively few parts.

Another object of the present invention is the provision of an improved puffer-type circuit interrupter in which blockage of the gas flow is afforded by the utilization of a hollow contact follower having a lost motion-connection with the moving hollow contact structure.

Another object of the present invention is the provision of an improved puffer-type circuit interrupter with a central arc-catcher that takes up a favorable location in a reduced electric field after a pre-selected displacement of a hollow contact follower by means of a lost-motion connection to the moving contact structure.

Further objects and advantages will readily become apparent upon reading the following specification, taken in conjunction with the drawings.

BRIEF DESCRIPTION OF THE DRAWINGS

FIG. 1 is a vertical sectional view taken through a puffer-type circuit interrupter, adaptable for outdoor use, and at a relatively high voltage, the contact structure being illustrated in the closed-circuit position;

FIG. 2 is a view similar to that of FIG. 1, but illustrating the disposition of the several parts during the pre-compression of the gas and prior to a separation of the contact structure.

FIG. 3 illustrates the disposition of the several parts at a later point in the opening operation with the gas flowing into the arc, and providing a double-flow gas-blast action;

FIG. 4 illustrates the fully-open circuit position of the puffer-type circuit interruption of the present invention, illustrating the absence of creepage surfaces between the separated contacts at widely-different voltages.

DESCRIPTION OF THE PREFERRED EMBODIMENT

Referring to FIG. 1 of the drawings, the reference numeral 1 generally designates a puffer-type circuit interrupter, including a pair of upstanding cylindrical-casing members 2, 3 formed of insulating material of the requisite strength, and clamped by annular support rings 4, 5, to an intermediately-disposed contact support plate 6. A separable contact structure 8 is provided, including a stationary tubular contact, designated by the reference numeral 10, and fixed in any suitable manner, as by a threaded adjustable connection 10a, to an upper support plate 12 having an upper dome portion 12a integrally formed therewith. An outwardly-jutting terminal-pad portion may be provided, designated by the reference numeral 14, to which a line connection L_1 may be secured.

Cooperating with the stationary tubular contact 10 is the movable contact structure 16, comprising a cluster of circumferentially-disposed contact fingers 17, encircled by a plurality of garter springs 19, and biased inwardly against the outer surface 10b of the stationary tubular contact 10.

The lower ends 19a of the contact fingers bear upon conducting surfaces within a recess portion 21, provided by an upstanding contact portion 23, formed as an integral part of an operating cylinder 25, which is moved downwardly by the operating rod 27 over the stationary fixed piston 29. As a result, as will be obvious, compression of the gas within the region 31 occurs upon downward driving motion of the surrounding puffer cylinder 25 over the fixed piston 29, and a forceable flow of gas upwardly through the plurality of openings 33 provided in the upper end of the piston cylinder 25.

As will be apparent from FIG. 2, there is a blockage of gas flow through the hollow stationary contact 10, and also through the hollow moving contact 16, because of the valve action of the hollow contact follower 35, biased upwardly by the spring 36, and having a lost-motion connection 37 with the movement of the several parts from the position of FIG. 1 to that of FIG. 2, a desirable precompression of the gas occurs within the region 31, without consequent venting action occurring, until the hollow contact follower 35 is picked up by the shoulder portion 39, as illustrated in FIG. 3 of the drawings.

Subsequent opening motion, of course, affords a venting action of the gas into both the tubular stationary contact 10 and also through the hollow moving contact structure 16, with the arc terminating at the arc horn 41, and also running upwardly along the inner surfaces 10c of the stationary contact 10. Because of the strong blast action from the pre-compressed gas, arc extinction quickly ensues, and further downward opening motion of the hollow operating cylinder 25 and the moving contact structure 16 provides a wide isolating break with no insulating surfaces between the separated contacts, which at high voltage could conceivably result in creepage paths with carbon formation and possible flashover. It will be noted, as shown in FIG. 4, that a wide open isolating gap 43 is provided in clean SF₆ gas 45 which fills the container 47, insuring thereby that no flashover occurs.

Preferably, sulfur-hexafluoride (SF₆) gas is utilized as the arc-extinguishing gas, but it will be obvious to those skilled in the art that other gases or fluids could be utilized. Certain aspects of the invention may have applicability in oil-filled circuit interrupters in which the oil flow is generated by piston action.

It will be noted that in my invention there is provided in a novel manner a double-flow blast action of the gas, utilizing the blocking action of the contact follower 35. This important double-flow action is accomplished by making the contact follower hollow, with an orifice opening 49 at the top. An additional important feature of my invention is the central arc-catcher rod 41, which, in the closed position of the contacts, protrudes through the follower orifice 49. In the arcing position, illustrated in FIG. 3, the arc-catcher 41 is below the orifice 49, where the hot arc terminal is out of highly-stressed contact gap region. However, the arc section inside the follower 35 is kept short, so that unnecessary

arc energy will be avoided that might lead to clogging of the restricted venting below the follower 35.

Although there has been illustrated and described a specific puffer-type circuit interrupter, it is to be clearly understood that the same was merely for the purpose of illustration, and that changes and modifications may readily be made therein by those skilled in the art, without departing from the spirit and scope of the invention.

What is claimed is:

10. 1. A circuit interrupter of the fluid-blast type, including separable-contact means comprising a relatively stationary hollow tubular venting contact and a cooperable hollow movable contact structure, a movable operating cylinder affixed to said movable contact structure, means defining a relatively stationary piston, said movable piston cylinder sliding over said relatively stationary piston to compress gas within the movable operating cylinder, an orifice structure carried by the movable operating cylinder and having an orifice opening closely encircling said stationary hollow contact, and a movable follower-contact structure movable with the movable contact structure and having a lost-motion connection with the movable operating cylinder to provide a valve action and thereby temporarily prevent the exhausting of gas through the separable contact structure.
15. 2. The combination according to claim 1, wherein the movable follower-contact is hollow.
20. 3. The combination according to claim 2, wherein the movable follower has an arc-catcher rod protruding through the opening thereof in the closed-circuit position of the circuit interrupter.
25. 4. The combination of claim 1, wherein biasing means are provided to bias the hollow contact-follower against the relatively stationary contact in the closed position of the interrupter.
30. 5. The combination according to claim 1, wherein the movable contact structure is hollow, and vents to the interior of a surrounding casing.
35. 6. The combination according to claim 1, wherein an upstanding casing structure is provided, said casing structure having a lower-disposed contact-support plate, and said stationary fixed piston is supported upwardly from said stationary plate structure.
40. 7. A high-voltage pumped-gas circuit interrupter comprising a pair of upstanding insulating casings having an interposed contact-support plate provided therebetween, line-terminal means provided at said contact support plate, an upstanding fixed piston rigidly secured to said control-support plate, a movable operating cylinder carrying a hollow movable contact structure sliding over said fixed piston, and relatively stationary hollow contact structure cooperating with said movable contact structure to establish an arc, and a concentrically-arranged interiorly-disposed contact follower of tubular configuration movable with the movable contact structure, and having a lost-motion connection with respect to said movable contact structure.
45. 8. The combination according to claim 7, wherein an arc-catcher rod is fixedly secured to said movable operating cylinder and extends in the closed position of the breaker through the orifice associated with the movable contact-follower.
50. 9. The combination of claim 8, wherein the tip of the said arc-catcher rod being placed in a position below the orifice in the hollow movable contact follower after a predetermined displacement of the said follower during the initial part of the contact opening movement.
